CARBONIZATION OF LIGNITE TO PRODUCE
MOTOR FUELS

Henry M. Noel, Summit, N. J., assignor to Standard Oil Development Company, a corporation of Delaware

Application December 1, 1948, Serial No. 62,837

2 Claims. (Cl. 196—55)

1

The present invention relates to an improved process for the efficient utilization of low grade carbonaceous solid material, such as lignite, peat, and the like, and, more specifically, to a process for converting such materials into more valuable products, including motor fuels, aromatic hydrocarbons, fuel gases, and the like.

It has long been known that solid fuel material such as lignite, peat, etc., could be converted into more valuable liquid and gaseous fuels and chemicals by low temperature carbonization and distillation. However, it has also been recognized that carbonization of such carbonaceous materials has been beset by many difficulties and disadvantages, both in the processing and in the nature of the products obtained. Thus among the principal constituents of the distillate obtained from low temperature distillation of low-grade carbonaceous materials such as lignite are phenolic materials. Not only do these products markedly decrease the value of the distillate as a motor fuel, but also the corrosion action of the product makes distillation and refining of the carbonization products a costly and difficult procedure. Furthermore, the presence of even minor quantities of phenolic and acidic constituents has the disadvantage of lowering the calorific value of the resulting liquid fuel, and also of raising the flash point of the product. Also, the presence of polyphenols and aminophenols resulting from such low-temperature carbonization accelerate polymerization and oxidation tendencies of the product. Though these phenolic and acidic constituents of the distillate may be removed by caustic washing, not only does this add another step to the process, but also it removes a substantial portion of the distillate and thus decreases markedly the amount of product available for motor fuel.

Heretofore and prior to the present invention it has been found that the production of undesirable phenolic distillation products may be to a large degree minimized and the yield of oil substantially increased by applying the so-called "methylation" technique to lignite distillation. Thus it has been found in laboratory operations that by adding minor quantities of calcium acetate, sodium carbonate, and iron filings, relatively high yields of oil containing a high proportion of aromatic constituents and very low in phenolic content are obtained. It is postulated that the reagents convert the phenolic material "in situ" into the corresponding methylated aromatic compound. Thus phenol is converted into toluene, cresols are converted into xylenes, xyle-

2

nols into mesitylene, etc., and since the aromatic hydrocarbons distill at substantially lower temperatures than the phenols from which they are derived, valuable high octane gasoline blending material is thus obtained.

Thus in 11 laboratory lignite distillation experiments, it was found that the phenol content of the lignite oil distilled from lignite samples from various French lignite fields ranged from about 22-50%. In the corresponding oils produced with methylation the phenol content was reduced to about 3%, and the aromatic hydrocarbon content greatly increased.

Furthermore, in the transformation of phenols into aromatics, the boiling range of the oil is greatly changed so that an average methylized lignite oil shows about 36% of fractions boiling in the gasoline range, whereas the unmethylized oil shows only 20%. This is due to the decrease in boiling point in going from a phenol to the corresponding methylated aromatic compound as indicated above. Thus toluene boils at 232° F., whereas the phenol from which it is derived by methylation boils at 366° F. The xylenes boil at about 280° F. whereas the original cresols boil entirely outside the gasoline range.

However, though this process has given excellent results in small scale laboratory equipment, it has hitherto been impossible to duplicate laboratory results in full scale equipment when attempts were made to commercialize this process. This is primarily due to the fact that very carefully controlled and uniform temperature in the lignite bed is absolutely essential, and such control and uniformity has hitherto been unobtainable by the use of conventional methods and processing equipment. Lack of narrow temperature control as experienced in commercial equipment is accompanied by substantial cracking of the primary distillation product, and the resulting material is high in polyolefin content thereby degrading and making it unsuitable for motor fuel purposes. Moreover the methylation reaction does not work when the temperature is outside of the critical range.

Thus for example, using the methylation process in small scale equipment a 10% yield of tar containing 30% naphtha and hydrocarbons boiling in the gasoline range were obtained from a Provence lignite, and the naphtha comprises 80% aromatics. This same lignite in a larger-scale horizontal cylindrical still using the methylation process, yielded only 6% of tar, containing only 15% naphtha, and of the latter only 25% was aromatic. Likewise, from a small scale distilla-

tion of a Midi lignite the yield was 12% tar containing 35% of naphtha, of which 65% was aromatic. The same lignite in a full scale "Ab der Halden" retort gave a yield of 10% of tar containing 20% naphtha which was practically devoid of aromatics. When one considers the high anti-knock characteristics of aromatic motor fuel, this yield was therefore, of little value. Again a laboratory methylizing distillation of Perigord lignite produced 12% of tar containing 30% naphtha which was 85% aromatic; using the methylation process again, the same lignite distilled in a full scale vertical rotary "Thermax" retort produced only 5% of tar containing 20% material boiling in the naphtha range of which only 20% was aromatic.

It was observed that in the full scale tests, even where no excessive cracking of product occurred, methylation was prevented due to the difficulty of maintaining the required methylizing temperature uniform and constant throughout the lignite bed.

It is the main object of the present invention to provide a means whereby low grade carbonaceous solids may be carbonized on a commercial scale to furnish high yields of aromatic material boiling in the naphtha range which are suitable as high anti-knock blending agents for motor fuels.

It is also an object of the present invention to provide a process whereby in commercial low temperature carbonization of low grade carbonaceous materials such as peat and lignite, temperature control and uniformity may readily be maintained.

It is another object of the present invention to provide means whereby heat required in the carbonization is generated by the partial combustion (to CO only) of portions of the lignite gas and carbonaceous residues and heat supplied to this zone by circulation of highly heated fluidized solids.

A still further object of the invention is to utilize semi-coke from the process to prepare high B. t. u. fuel gas and/or hydrocarbon synthesis gas.

Other and further objects of the invention will be disclosed hereinafter.

The new process affords the above-mentioned advantages, as well as full and easy adaptability to changes in the character of the starting materials. These and other advantages will be fully understood from the following description and the drawings.

Referring now to Figure 1, numeral 1 denotes the crusher and mixer which is employed to reduce a solid low grade carbonaceous fuel, such as lignite or peat, to a finely divided form, for example, preferably of the order of below 50 mesh, or even less than 100 mesh, although even small lumps, say $\frac{1}{4}$ to $\frac{1}{2}$ inch size may be employed. Through line 2 are added the chemicals employed in conjunction with the methylation process. Though the quantities employed may vary within fairly wide limits depending upon the nature of the lignite or peat, generally about 2-6% of calcium acetate, 1-4% of sodium carbonate, and up to 2% of powdered iron or iron filings may be employed, based on the quality of lignite to be treated. However, under certain circumstances, iron filings are not required for the reaction. As disclosed more fully below, the amount of sodium carbonate added may in accordance with the process of the present invention, be progressively decreased. The salts may

be added either in the dry form or in aqueous solutions, but however they may be added, it is highly desirable that they be mixed with the crushed carbonaceous material into as intimate a mixture as possible. If desired, the powdered iron may be substituted in whole or in part by iron oxide and in certain cases iron is not required at all.

The finely ground mixture of carbonaceous solids and chemicals is passed from mixer 1 and line 3 to line 4 wherein it is thoroughly dispersed in a stream of "aeration" gas which is preferably light hydrocarbon gases from the process, as disclosed more fully hereinafter. The powdered feed in the dispersion is said to be in fluidized form because in this form it is capable of flowing through pipes, valves, ducts, etc., much like a liquid, showing both static and dynamic heads. The fluidized stream is passed through line 4 into the lower portion of carbonization chamber 5 which is in the form of a vertical cylinder. A grid or screen 7 is located in the lower portion of chamber 5 to support a fluidized bed and to afford good distribution of the upflowing fluidizing gases. Also fed to carbonizer 5 through lines 3 and 4 is a stream of hot combustion residue from the gasification stage, as will be made clear hereinafter. These finely divided solids, having a temperature of from about 1400° to 2000° F., and fluidized if required, by slow currents of fuel gases admitted through aeration taps 9, are passed into contact with cold feed stock and thence into carbonizer 5 at such a rate as to maintain the desired temperature level therein, as described below.

The mixture of lignite or peat, combustion residue, and aeration gas comprising light ends from the subsequent distillation is discharged into the bottom of carbonizer 5, the suspension entering below screen or grid 7 and then passing upwardly. Due to the superficial velocity of said gas stream, which is maintained within the limits of about 0.2 to 5 feet per second, the carbonaceous material and the reagent chemicals are formed into a turbulent ebullient mass, resembling a boiling liquid, having a well-defined upper level. The temperature in this zone is capable of very careful regulation and control, and heat is distributed rapidly through the fluidized mass in the carbonization chamber because of the high degree of agitation maintained therein. The temperature is maintained in the range of about 800° F.-1100° F. preferably between 850° to 900° F., and the heat required for the carbonization is furnished substantially by the heat of the hot residue recycled from the subsequent gasification-combustion zone, which is operated preferably at temperatures substantially above the temperature of the carbonization zone.

As a result of the carbonization of lignite in chamber 5 in the presence of the reagent chemicals, substantial quantities of aromatic hydrocarbons boiling in the naphtha range are formed, with only minor quantities of phenolic compounds. As a result of the excellent heat transfer and control characteristics of the present operation, the temperature of the bed of lignite undergoing distillation is uniform, and cracking and decomposition is substantially minimized, as opposed to prior experiences in fixed or moving bed commercial carbonization processes with the reagent chemicals.

The gaseous products are continuously withdrawn from carbonizer 5 through a dust separator 10 such as a cyclone, which has a dip pipe 11 ex-

tending below the upper level of the fluidized bed for returning separated dust. The volatile products are passed through line 12 and cooler 13 to separator 14, where means are provided for segregating tar, light oils, aromatic hydrocarbons, ammonia and gas. Thus condensate comprising aromatics as xylene, toluene, benzene, mesitylene, etc., and also heavier distillation products such as tar and middle oil may be withdrawn from separator 14, through line 15 and passed to the products recovery system (not shown) where the aromatic hydrocarbons boiling in the naphtha range may be separated from higher boiling materials by fractional distillation.

The lignite gas may be withdrawn overhead from separator 14 through line 16. It is preferably scrubbed free of aromatic material in a conventional oil scrubber 17 or charcoal absorber. The gas comprising low molecular weight hydrocarbons, hydrogen, carbon monoxide, etc., is compressed and passed in part to line 4 to fluidize the powdered feed to the carbonization stage, and the balance may if desired, be passed to the combustion-gasification stage as disclosed more fully below. Also, the gas may be freed from H_2S by any known process of desulfurization prior to its subsequent use, and, if desired, some of the gas may be withdrawn through line 18, carbon dioxide removed by scrubbing with alkali or amino alcohols, and a very high calorific fuel gas is thus obtained.

Returning now to carbonizer 5, an elongated vertical pipe 19, opening into a pocket below the distillation zone is provided to carry a fluidized stream of solids from the carbonization chamber 5. Semi-coke and the solid products of the lignite distillation and chemical reaction are passed through standpipe 19 to line 21 where they are dispersed and suspended in a stream of superheated steam. The fluidized stream is passed into the lower portion of a gas generator 20, which is of essentially the same type as the carbonizer 5 and is fitted at its lower end with an inlet line 22 for admitting oxidizing gas, such as air or preferably oxygen. Said oxidizing gas may also be added to the fluidized stream in line 21. Also admitted to zone 20 may be gas from the lignite distillation, which is admitted through line 23.

The fluidized semi-coke in generator 20 is in the form of a turbulent mass fluidized by the upward flowing gases and superheated steam. The gasification of the carbon by the oxygen and steam proceeds rapidly to form carbon monoxide and hydrogen. The heat required for the endothermic gasification reaction is supplied in part by the limited combustion of part of the carbonaceous solids in reactor 20 by the oxygen admitted through line 22, and also by limited combustion of the lignite distillation gas by oxygen from the same source. The total supply of oxygen is carefully controlled to produce synthesis gas and also to generate sufficient heat by combustion to satisfy the heat requirements of the carbonization step. Thus as a result of the concomitant gasification of carbon and controlled combustion of normally gaseous hydrocarbons, a gas rich in H_2 and CO is produced, suitable for a high calorific fuel gas or for the catalytic production of high octane hydrocarbons by the hydrocarbon synthesis reaction. The temperature maintained in reaction zone 20 is in the range of about 1200° - 2000° F., preferably about 1700° - 1900° F. The gasification products are withdrawn through dust separator 24, such as a cyclone and

line 25 and may go to product storage, purification for sulfur removal and to the hydrocarbon synthesis plant, or combined with the product withdrawn through line 18 for use as high calorific fuel.

A fluidized stream of hot solids comprising ash and the products resulting from the high temperature treatment of the reagent chemicals, principally calcium oxide, sodium carbonate, and minor proportions of iron oxide, is continuously withdrawn from gas generator 20 through pipe 26 at a rate determined by the heat requirements in the carbonization zone. Waste ash may be passed through heat exchangers before being discharged from the system. The balance of the ash withdrawn from generator 20 is passed through "aerated" lines 8 and 4 back to carbonizer 5 to supply the heat requirements therein.

Not the least of the advantages entailed in the recycle of hot ash to the carbonization zone is the economic utilization of the sodium carbonate content thereof. Thus the supply of that chemical fed through line 2 to vessel 1 may be gradually decreased and only enough need be added 25 to correspond to the quantity being withdrawn through line 27 along with waste ash. This represents an appreciable saving in chemical costs.

It will be understood that the embodiment of the invention as described above admits of numerous modifications. Among such are modifications wherein the carbonization of the lignite and combustion-gasification of the semi-coke may be carried out in a single vessel containing an inner and an outer concentric reaction zone and 35 valuable heating economies may thus be realized.

Figure 2 represents one type of such vessel. The reagent chemicals and powdered lignite or peat are passed through line 40 and are suspended in line 41 by lignite gas from the carbonization 40 process as described below. The solids in gas suspension are injected tangentially into the outer carbonization zone of vessel, and the dilute suspension is subjected therein to carbonization conditions, the heat being supplied both indirectly through the walls of inner combustion-gasification zone 43 and directed by recycle of ash as described below. Volatile products comprising lignite gas, aromatic hydrocarbons boiling in the gasoline range, tar, etc., are withdrawn overhead through cyclone 44 and line 45. The carbonization residue, as a result of the centrifugal action associated with the tangential injection of the suspended particles and their passage about the outer circumference of inner vessel 43, drop out of 55 the dilute suspension and pass to the conical bottom of vessel 50. If desired, aeration gas may be admitted through taps 51 to maintain a fluidized dense bed of semi-coke and ash in the bottom section of this zone. As a result of the pseudo-hydrostatic head on the fluidized bed, and as a result of the suction action associated with the injection of oxygen, steam, and lignite gas into the inner gasification zone 43 of vessel 50 through line 47, coke and ash are continuously withdrawn 60 from carbonization zone 42 to gasification zone 43 through lines 46 and 47. Within zone 43 gasification of coke and combustion of coke and of lignite gas are carried out as described above in connection with vessel 20. Reaction conditions 65 within zones 42 and 43 are similar to those in zones 5 and 20 respectively. In gasification zone 43 synthesis or fuel gas is withdrawn upwardly through line 48, whereas ash comprising the inorganic chemical reaction products named above 70 are withdrawn downwardly through line 49. The 75

desired quantity of ash to be recycled to carbonization zone 42 to furnish part of the heat and alkali content thereto is withdrawn through line 52, the balance being withdrawn from the system.

Figure 3 is another modification of the above process, in which the carbonization zone 60 is the inner zone and the gasification zone 70 is the outer zone. Powdered feed, comprising lignite and reagent chemicals is added through line 61, entrained by product lignite gas in line 62, and injected into carbonization chamber 66, which is at carbonization conditions with a temperature level of about 800°-1100° F. Carbonization distillate passes overhead through cyclone 63 and line 64 to the product recovery system. Coke and ash settle and pass to the bottom of inner zone 60 and through pipe 65 to line 66 wherein they are suspended by a stream of gas comprising superheated steam, oxygen, and lignite gas. The suspension is injected into outer gasification zone 70 wherein the semi-coke is gasified and lignite gas combusted as described heretofore. Synthesis or fuel gas may be withdrawn through line 67. The ash particles pass downwardly from the dilute suspension into the ash bed at the bottom of zone 70. To furnish part of the heat requirements in zone 60, a portion of the ash is passed through line 68 into line 62 and is suspended in the upwardly flowing stream of lignite gas and fresh feed. Waste ash is withdrawn through line 69.

These last two embodiments of the invention are particularly conducive to heat conservation and control, as well as economizing in reactor construction.

In a further embodiment of the invention advantage is taken of the high heat carrying properties of the ash being recycled from the gasification-combustion zone 20 to carbonization zone 5 in Figure 1. It may, under certain circumstances, be desirable to cycle the heavier portion of the lignite tar, which is relatively unaffected by the methylation process, to carbonizer 5, and to subject the tar to an endothermic cracking process with the hot recycled ash furnishing the heat thereto. In this process the tar fraction from the lignite distillation process is injected into the hot recycle solids stream through line 28 prior to the injection point of the stream into the carbonizer. The heavy tar is then cracked at a much higher temperature than that at which it was originally produced, and the overall naphtha and gas yields are correspondingly increased. To furnish the necessary extra heat thus required, the rate of hot solids circulation is correspondingly increased.

Alternatively, the hot ash in line 27 not recycled to the carbonizer may be employed to crack the lignite higher boiling tar fraction in a separate cracking vessel (not shown) for conversion into gasoline and gas oil fractions.

Thus when operating in accordance with the present invention there will be produced from one ton of Texas lignite, about 30 gallons of methylated tar in addition to the hydrocarbon synthesis or fuel gas. The methylated tar contains about 30% of clear aromatic hydrocarbons boiling below 400° F. as a result of the reaction between the phenolic components and the added chemicals. Thus the valuable character of the tar from this process, coupled with the fact that lignite gas produced by this process is high in hydrogen content (about 20%), as distinguished from the ordinary coke oven products makes the

process of the present invention a particularly attractive method of carbonizing lignite and simultaneously producing synthesis gas.

Mention has not been made of various accessory pieces of equipment which normally are employed in a commercial plant. Thus in the interest of good heat economy, various heat exchangers and economizers are employed to utilize available heat in the most efficient manner, and, in order to control the process, pumps, compressors, valves, flow meters are included in the equipment. Cooling means, internal or external, may be employed to aid in the control of carbonization temperatures.

The foregoing description, though illustrating specific applications of the invention is not intended to exclude other modifications obvious to those skilled in the art, and which are within the scope of the invention.

What is claimed is:

1. An improved continuous process for producing valuable motor fuels from low grade carbonaceous solids of the type of lignite and peat which comprises initially mixing finely divided carbonaceous solids with minor proportions of a carboxylic acid salt of calcium and 1 to 4% of extraneous sodium carbonate in a mixing zone, passing a stream of said finely divided mixture into a carbonization zone, forming a fluidized mass of solids therein maintained at a carbonizing temperature of about 800° to 1100° F., subjecting distillable portions of said carbonaceous solids to a chemical reaction in said carbonization zone whereby phenolic constituents of said portions are converted into aromatic hydrocarbons, removing volatile products from said carbonization zone, leaving a coky residue in finely powdered fluidized form, withdrawing from said carbonization zone a stream of fluidized carbonaceous coky solids, containing a minor proportion of sodium carbonate, passing the same directly into a gasification zone to form a fluidized mass of solids therein, reacting said mass with steam at a gasification temperature of about 1400° to 2000° F. to form a gas rich in H₂ and CO, adding oxygen and a fuel gas to said gasification zone, supplying all the heat required for said gasification reaction above and beyond the sensible heat of said stream, steam, oxygen and added fuel gas by controlled combustion of said fuel gas and said carbonaceous solids to form further quantities of gas rich in H₂ and CO, withdrawing a gas rich in H₂ and CO from said gasification zone, withdrawing hot fluidized solid combustion residue containing sodium carbonate from said gasification zone, discarding a minor portion of said residue adequate to prevent excessive solids build-up in said zones, feeding the remainder of said hot combustion residue to said carbonization zone to supply heat required therein, progressively decreasing as the reaction proceeds, the amount of extraneous sodium carbonate added to said mixing zone at a feed rate of extraneous sodium carbonate corresponding to the amount of sodium carbonate discarded with said discarded minor portion and further increasing the yield of product boiling within the gasoline boiling range by recycling at least a portion of the distillation products from said carbonization zone boiling above the gasoline boiling range and subjecting said material to a cracking reaction by contacting with hot ash recycled from said gasification zone at a temperature above that at which said products were distilled.

2. The process of claim 1 wherein said portion

of the distillation products boiling above the gasoline boiling range is injected into said hot recycled ash at a point prior to the introduction of said ash into said carbonization zone.
